UNITED STATES PATENT OFFICE.

MAXIMILIAN H. MOSKOVITS, OF KANSAS CITY, MISSOURI.

FURNACE-GRAVE.

SPECIFICATION forming part of Letters Patent No. 399,688, dated March 19, 1889.

Application filed June 21, 1888. Serial No. 277,788. (No model.)

To all whom it may concern:

Be it known that I, MAXIMILIAN H. MOSKOVITS, of Kansas City, Jackson county, Missouri, have invented certain new and useful 5 Improvements in Furnace-Grates, of which the following is a full, clear, and exact description, reference being had to the accompanying drawings, forming a part hereof.

My invention relates to furnaces having automatic feeding and cleaning devices; and it may be said to consist in the novel construction, combination, and arrangement of parts, hereinafter set forth, and pointed out in the claims.

15 In the drawings, which illustrate the manner of carrying out my invention, Figure 1 is a broken sectional side elevation of my improved furnace-grate as applied to a steam-boiler furnace with horizontal boiler. Fig. 2 is a front elevation of same without doors beneath the grate-bars. Fig. 3 is a detail view of bearing ball or roller used in making up the invention. Fig. 4 is a detail plan view of the under side of a grate-bar that is used in 25 the invention. Fig. 5 is a sectional detail view, in perspective, of the upper end of a grate-bar, the section being taken on line *y* *y*, Fig. 4. Fig. 6 is a detail view of a hand-lever and connections for varying the inclination 30 of the grate-bars. Fig. 7 is a detail view of a multiform crank-shaft used for communicating motion to the grate-bars, and Fig. 8 is a face view of a bearing-bar which supports the ends of the grate-bars.

35 The furnace-front may be of the usual form, with the exception of ordinary feeding and ash-pit doors, which are entirely abandoned, that part of the ordinary furnace-front below the lower boiler-line being entirely removed, 40 preferably, so that the bottom of the grate-bars and all of interior of furnace below the grates are perfectly exposed to view from a position in front of the boiler. If so desired, however, I may close the front of the furnace 45 below the grate-bars and above the floor-line *z* *z* by means of doors *B* of any ordinary form.

Each side of the furnace below the grate-bars consists of a heavy solid cast-iron frame-plate, *A*, extending from the front to about 50 the inner ends of the grate-bars, the front ends of which support the cast-iron front car-

rying the feed-hopper *C*. These side frames are bound together by means of bearing-bars *E*, which extend across from one to the other and upon which the grate-bars *D* are mounted. 55 They are made very heavy and support all the other work independently of the brick-setting, and are preferably mounted upon suitable wheels or rollers, *a*, and removably located in ash-pit *A'*, as shown more clearly in Fig. 1. This pit not only extends under the boiler a sufficient distance to form an ordinary ash-pit, but it extends a sufficient distance in front of the boiler to allow the entire frame *A* (supporting the feeding apparatus) 60 to be withdrawn from under the boiler whenever occasion may require.

The pit *A'* is provided with a suitable cover, *d*, which may be quickly removed whenever required, in such instances as drawing the 70 fire or cleaning out ashes.

In front of the boiler, and above the upper ends of grate-bars *D*, a large iron hopper, *C*, is attached to the cast-iron front, extending across the front, its length being equal to the 75 width of the grate-surface and its capacity varying accordingly. The bottom of the hopper *C* is formed by the upper ends of grate-bars *D*, which extend outwardly a sufficient distance for such purpose. 80

The grate-bars *D* are inclined at about an angle of thirty-four degrees from the horizontal, corresponding to the kind of fuel in use, and are made with short longitudinal bearing-ribs *e*, projecting from the under side 85 of their lower ends, which rest within an encircling groove, *f*, formed on the outside of bearing-balls *F*. Said balls are located in elongated ball-sockets *h*, formed in transverse bearing-bars *E*. Said sockets are provided 90 with an opening or slit, *i*, in the bottom for egress of dirt and grit which might otherwise collect in them and cause friction to be generated.

The upper ends of the grate-bars are provided upon their under surface with elongated ball-sockets *e'*, similar to those in bars *E*, and they rest upon suitable friction balls or rollers, *F*, located in another bearing-bar, such as *E*, before described. Said grate-bars are 100 constructed with a solid upper end, *b*, provided with steps or corrugations *b'* upon its upper

- side and with a fire-surface upon its lower portion, which is preferably made up of short transverse zigzag webs 10. Of course, however, the fire-surface may be constructed in 5 any other preferred form that will answer the purpose. It will be observed that the steps b' are continued over the entire upper surface of the grate-bars.
- The transverse zigzag webs 10 are located 10 at sufficient distance from each other to afford ample inclined openings into the burning fuel, insuring full supply of air, and not only promoting combustion, but also keeping the grate-bars comparatively cool and preventing them from being warped, melted, and burned out.

On the inner plate, c, of the feed-hopper I locate a vertically-sliding feed-plate, 13, which can be moved up and down by means of a 20 suitable screw and hand-wheel, 14, or by any other preferred means, so as to close the feed-opening 12 more or less. The bearing-sockets h in bar E at lower ends of grate-bars are inclined, as shown, so that as said bars are 25 reciprocated longitudinally an up-and-down movement will be imparted to their lower ends, thereby causing them to be oscillated upon the upper bearing-bar. Each alternate bar is moved in the same direction by means 30 of the several cranks on shaft H. The grate-bars oscillate upon supporting-bar F and do not follow the circular movement of cranks 16. Each grate-bar making up the grate has a rising-and-falling and endwise movement im- 35 parted to it by means of multiform crank-shaft H, having a number of short cranks, 16, formed on it which engage a suitable bearing-lug, 17, depending from the under surface of grate-bars D near their upper ends. The lower 40 ends of the bars move up and down; but their upper ends rest on upper bearing-bar, and therefore do not follow the up-and-down movement of cranks 16. A continuous rotary motion is imparted to this crank-shaft by means 45 of a worm-gear, 18, and belt 19, or other suitable gearing. (Shown at the right-hand side of Fig. 2.) The motion is such that one-half of the series of bars (as thus arranged) lift the body of the fuel from the bars between them, 50 (which are moving in an opposite direction,) and cause said fuel to move evenly down toward the rear of furnace. The movement of the fuel is still further aided by the steps formed on the upper side of the grate-bars, 55 said steps taking hold of the fuel (as it were) and pushing it toward the rear of the furnace. The motion is positive and uniform, but may be varied as occasion requires. The fuel, entering the furnace by way of the feed- 60 opening 12, is delivered at the top of the grate-bars, whence the motion of the grate-bars combined with gravity causes it to move evenly along the inclined grate-bars toward the rear of the furnace.

65 All fuel on the grate-bars moves simultane-

ously and continuously. This movement is positive and uniform, although it may be accelerated or retarded as the demand for steam production varies.

The constant movement of the grate-bars 70 prevents the formation thereon of clinkers. All the fuel is consumed on the inclined grate and the feed is to be regulated accordingly.

The clinkers and ashes and other incom- 75 bustible matter pass from the grate-bars (through passage 50, formed in the brick-work at the lower ends of said bars) to the ash-pit below, as shown in Fig. 1.

The feeding motion may be varied in vari- 80 ous ways—for instance, by changing the speed of the driving-gearing or by imparting a different degree of inclination to the grate-bars, which latter I accomplish as follows:

The bearing-bars E at lower end of grate-bars are provided with vertical shanks 60, 85 which have friction-wheels 61 at their lower ends. These friction-wheels rest upon cams 62, mounted upon transverse shaft 63. By means of a suitable hand-lever, 64, which ex- 90 tends upwardly and outwardly a suitable dis- tance to be conveniently reached the shaft 63 may be slightly revolved in its bearings, caus- 95 ing the cam 62 to raise or lower the shanks 60 and bearing-bar E, carrying the lower ends of the grate-bars, thus giving more or less incli- 100 nation to said grate-bars, and causing the fuel to travel downward upon them faster or slower and in greater or less quantity, as the demand for steam requires.

The power required to drive the entire ap- 100 paratus will be but a trifling amount, because the bars are entirely supported on balls F.

The machine may be driven by a belt from any convenient shaft; or a small special en- 105 gine may be used for this purpose, as may be preferred by the proprietor of the plant.

Having thus described my invention, what I claim is—

1. The improved grate-bar constructed solid for a considerable portion of its length and with the remaining portion of its length in the form of a fire-surface composed of short zigzag webs which are disposed transversely, the upper surface of said bar being stepped or cor- 110 rugated, substantially as described. 115

2. The combination of inclined grate-bars provided with suitable bearing-sockets near each end, friction-balls located in these sockets, a transverse bearing-bar, E, provided with depending shanks 60 and upon which the 120 lower ends of said grate-bars rest, cams 62, which engage the lower ends of said shanks to raise and lower same, and a hand-lever for ro- 125 tating said cams, substantially as described.

In testimony whereof I affix my signature in presence of two witnesses.

MAXIMILIAN H. MOSKOVITS.
